Ferdinand Mehlis

UNITED STATES PATENT OFFICE.

FERDINAND MEHLIS, OF BERLIN-BUCHHOLZ, GERMANY.

EMERGENCY BEARING FOR RAILWAY CARS.

1,422,596.

Specification of Letters Patent. Patented July 11, 1922.

Application filed December 28, 1921. Serial No. 525,440.

To all whom it may concern:

Be it known that I, FERDINAND MEHLIS, a citizen of the German Republic, and resident of Berlin-Buchholz, Germany, have invented a certain new and useful Improved emergency bearing for railway cars adapted for use as a substitute for axle boxes of railway cars, of which the following is a specification.

10 In the case of railway-collisions, derailments of whole trains or merely single cars (which latter occurrences happen frequently upon shunting depots), and the like, longer interruptions of service are caused especially by the pedestal horns and the axle boxes of the cars being broken whereby removing the damaged cars from the place of accident is made very difficult owing to the impossibility of supporting the car bodies by the car-axles. Clearing the tracks requires, thus, much time which is another disagreeable consequence of an accident of the one or the other kind.

25 The emergency-bearing forming the subject matter of this invention is intended as a provisional substitute for a broken axle-bearing and permits of supporting the car-body by the axle-journals. It allows of a convenient and quick connection with the bearing- or supporting springs of the car. These springs, the axles, and the wheels, remain in most cases undamaged, and it is then, with aid of the novel emergency bearing, possible to quickly remove the 35 damaged cars from the rails and clear the tracks.

30 My invention is illustrated in the accompanying drawing, in which Figure 1 is a side-view of a railway-car axle-bearing provided with an emergency bearing in lieu of the original axle-box; Figure 1^a is a detached view and shows the emergency-bearing alone; Figure 2 is a vertical transverse section through the parts shown in Figure 1; Figure 2^a is a transverse section through the parts shown in Figure 1^a; and Figure 3^a is a plan of the same parts.

40 The emergency-bearing is made of malleable cast-iron or band-steel or another suitable metal and consists of one piece bent into a certain shape, viz: its middle part forms

an inverted U a, the legs a¹ a² of which are integral with upwardly extending legs b¹ b² having at their upper ends horizontal extensions or flanges c¹ c². The semi-circular 55 middle part a corresponds to the diameter of the axle-journal, the flanges c¹ c² serve for connecting the emergency-bearing with the springs, and the vertical legs b¹ b² are the carrying parts proper which transfer the 60 weight of the car to the axle journals.

Connecting the parts c¹ c² with the springs may be effected in various manners. In the form of construction shown as an example, the parts c¹ c² have downwardly bent 65 thickened ends d¹ d² and between these latter and the vertical parts b¹ b² lie horizontal transverse plates, viz one of a pair of plates e¹ e¹ and one of a pair of plates e² e². The other plate of each pair lies upon the bearing-springs f and the two associate plates are connected with each other by bolts g¹ g¹ and g² g².

70 The length of the U-legs a¹ a² is such that the emergency-bearing cannot jump off the axle-journals. i is an oil-hole in the curved middle part of the U, f² is the spring-buckle, and f¹ the known downward extension of this latter. The curved part of the U may have oil-grooves to be fed from the 75 oil-hole, as shown in Figure 3^a, and, if desired, an oil-cup may be placed upon that hole. The complete emergency bearing as shown in Figures 1^a, 2^a, and 3^a, has all its parts assembled. To apply it, only one of 80 the bolts g¹ and one of the bolts g² need be removed when the bearing may be laterally shoved over the springs and then firmly connected with them by means of the removed bolts g¹ g².

90 Having now described my invention, what I desire to secure by a patent of the United States is:

1. An emergency bearing for railway cars, comprising, in combination, a structure consisting of a middle part forming an inverted U, legs extending upwards from the sides of said middle part, and horizontal flanges extending from the upper ends of said legs to opposite directions; and means for affixing said structure to the bearing-springs of 100 a railway car.

2. An emergency bearing for railway cars, comprising, in combination, a structure consisting of a middle part forming an inverted **U**, legs extending upwards from the sides 5 of said middle part, and horizontal flanges extending from the upper ends of said legs to opposite directions; two pairs of transverse plates adapted to be arranged below

and above the bearing springs of a railway car, and four pairs of bolts with nuts 10 adapted to connect the laterally projecting ends of said plates with each other so as to secure the emergency bearing to said bearing springs.

FERDINAND MEHLIS.
